T. PULLEN.
BREAKING FLAX AND HEMP

Patented June 20, 1816.

Thomas Peckham
Salem Patent

2619X

The Schedule referred to in this Salem Patent and making part of
the same containing a description in the words of the said Thom-
as Peckham himself of his machine for breaking stone or tile.

The machine consists of a lever with a pivot through the centre which
pivot passes through two blocks of timber that is on on each side
which blocks are supported by four posts two on each side of the lever
and the ends of the blocks are tenanted and pass through the mortises
in the ends of the posts which mortises are sufficiently large and
will the blocks up and down some inches, thereby permitting the
lever to act with more force upon the brake which brake is sim-
ilar to the breakers now in use by hand & is connected to the end
of the lever by means of a rod of wood or iron, having a pivot or
joint at each end. the other end of the lever is connected to a
crank or wheel the same way by means of a rod which has its
regulating motion by means of a Balance wheel, the wheel is put
in motion by means of a hand spring or under a large wheel de-
signed to go by a horse or any other mechanical movement.
The upright posts are fixed with two rollers to act a guide to
the lever or rod.
